UNITED STATES PATENT OFFICE.

JAMES A. WHEELER, OF NEW YORK, N. Y., ASSIGNOR TO ALIGNUM ASBESTOS LUMBER COMPANY, OF SOUTH RIVER, NEW JERSEY, A CORPORATION OF NEW JERSEY.

COMPOSITE TILE.

No. 921,036.

Specification of Letters Patent.

Patented May 11, 1909.

Application filed March 6, 1908. Serial No. 419,429.

To all whom it may concern:

Be it known that I, JAMES A. WHEELER, a citizen of the United States, and resident of New York, in the county of New York, in the 5 State of New York, have invented new and useful Improvements in Composite Tiles, of which the following, taken in connection with the accompanying drawings, is a full, clear, and exact description.

10 This invention relates to the class of tiles which are used for constructing partitions, ceilings and floors of buildings and other analogous architectural structures.

The object of the invention is to provide 15 tiles of the aforesaid class which shall be capable of being readily and conveniently set up to form hollow walls or parts of walls or partitions, or wainscoting, or panels in buildings, or laid to form floors or ceilings with or 20 without mortar, and without requiring stud- dings, tension-rods, or stiffening bars, or lattice to sustain the tile-structure, and which tiles shall also possess strength, durability 25 and ability of resisting transmission of sounds. And to that end the invention consists in the novel construction of the tile as hereinafter described and summed up in the claims.

In the annexed drawings Figure 1 shows 30 inner face views of the slabs which form the tile; Fig. 2 is a transverse section on the line —X—X— in Fig. 3; Fig. 3 is a transverse section on line —Y—Y— in Fig. 2; Fig. 4 is a face view of a wall formed of my improved 35 tiles and showing in dotted lines the internal tying and reinforcing-ribs and flanges formed on the slabs, which constitute the faces of the wall; Fig. 5 shows inner face views of a modification of the aforesaid slabs; Fig. 6 is a face 40 view of a tile formed of said slabs and showing in dotted lines the internal flanges and ribs; Fig. 7 illustrates inner face views of further modifications of the construction of the aforesaid slabs; Fig. 8 is a face view of a tile 45 formed from said slabs, the dotted lines indicating the relative positions of the internal flanges and ribs; and Fig. 9 is a transverse section taken in a plane parallel with the faces of a wall formed from tiles embodying 50 further modifications of my invention.

Similar letters of reference indicate corresponding parts.

—A— and —B— represent the two separate slabs which I preferably mold from suitable cement which solidifies or sets to a stone-like hardness and compactness. These slabs are disposed parallel face to face and are formed with ribs on their inner sides to form spaces between said slabs and also brace the slabs. A wall built from such tiles is thus 55 made hollow, light, strong and to a great degree capable of resisting transmission of sounds through it.

The ribs and flanges on each slab are arranged to meet and interlock with those on 60 the companion slab and thus form a bond between the two slabs.

Figs. 1 and 2 and 3 of the drawings show the slab —A— formed with the marginal flanges —a— and with diagonal ribs —b—, 70 which latter extend from points at short distances from the center of the slab partway (preferably about midway) toward the corners of the slab. The companion slab —B— is formed with ribs —c—c— extending horizontally and vertically from the center of the slab and terminating near the edges thereof. The four corner-portions of the slab are formed with diagonal ribs —d—d— extending from points at short 75 distances from the corners partway or about midway toward the center of the slab. The inner extremities of the ribs —b— and the outer ends of the ribs —c— and —d— are beveled at their sides to V-shaped points 80 —i—i—, while the inner sides of the marginal flanges —a— are provided with V-shaped notches —e—e—. In uniting said slabs they are placed with their ribbed faces one upon the other and when thus placed 85 the right angled central ribs —c—c— of the slab —B— pass between the four inner ends of the ribs —b—b— of the slab —A—, while the outer ends of the ribs —c—c— enter into the notches —e—e— of the marginal flanges 90 —a—a—, and the diagonal ribs —d— meet at their inner ends the outer ends of the diagonal ribs —b—, while the outer ends of the ribs —d— lie with their V-shaped points 95 —i— in the four corners of the marginal flanges —a—a—. The V-shaped ends —i—i— of the ribs —c— and —d— are 100 thus interlocked with the flanges —a—a— while the similar shaped ends —i—i— of

the ribs $b-b$ are interlocked with the junction of the four ribs $c-c$ as shown in Fig. 3 of the drawings.

In building a wall of such tiles as represented in Fig. 4 of the drawings, the successive tiles may be tied together either with or without mortar, or by means of screws, or nails, or wires passing through the edges of the tiles at their junctures.

- 10 I do not limit myself specifically to the hereinbefore described construction as it admits of modifications of its details. One of said modifications is illustrated in Figs. 5 and 6 of the drawings in which A^1 and B^1 designate the two slabs of which the tile is formed. The tile A^1 is formed on its inner side with the two horizontal ribs $f-f$ which intersect the vertical ribs f^1-f^1 at the center of the tile. Each of 15 these ribs is formed at its outer end with an enlargement g which is beveled V-shape toward the edge of the slab. At corresponding sides of the ribs $f-f^1$ are diagonal ribs h each of which extends 20 from the enlargement g midway the next of said enlargements and from the end of the rib h extends another diagonal rib h^1 partway toward the intersection of the horizontal and vertical ribs $f-f^1$. 25 From the opposite side of each enlargement g extends a diagonal rib j meeting the junction of the ribs $h-h^1$ and extending thence partway toward the corner of the slab as shown at j^1 and terminating 30 with an enlargement t which is beveled V-shaped toward said corner. The inner side of the companion slab B^1 is formed 35 with the marginal flanges $n-n$ and with V-shaped notches n^1 in the centers of the inner sides of said flanges. From one 40 side of each of these notches extends about half way toward the next succeeding notch a diagonal flange o , from the inner end of which extends partway toward the intermediate corners of the tile a diagonal rib o^1 . From the opposite side of each 45 notch n^1 extends halfway toward the preceding notch a diagonal rib p which meets the junction of the ribs $o-o^1$ at which point a diagonal rib p^1 extends from the rib p partway 50 toward the center of the slab and terminates with an enlargement p^2 , which is V-shaped and pointing toward said center. In 55 placing the slab A^1 with its ribbed side upon that of the slab B^1 the diagonal ribs of each slab lie parallel and contiguous to those of the companion slab, and the inner ends of one set of ribs abut against the enlargements p^2 on the ends of the other 60 set, while the outer ends of the diagonal ribs $j-j^1$ engage the corners of the flanges $n-n$, and the ends of the horizontal and vertical ribs f and f^1 enter into 65 the notches n^1 in the aforesaid flanges

n as indicated by dotted lines in Fig. 6 of the drawings. Said flanges are thus interlocked to retain the slabs A^1 and B^1 in their position in relation to each other. Said slabs are tied together by any suitable means as hereinbefore stated.

My invention may be further modified in the manner illustrated in Figs. 7 and 6 of the drawings, in which A^2 and B^2 represent the two slabs of which my improved tile is composed. The tile A^2 is formed with horizontal ribs $r-r$ and vertical ribs r^1-r^1 terminating in angular heads r^2 near the edges of the slabs. The inner ends of said ribs meet with four diagonal ribs r^3 extending around the center of the slab. Central between each horizontal rib r and adjacent vertical rib r^1 is a diagonal rib s terminating in a laterally enlarged head s^1 in proximity to the corner of the slab. The inner end of said diagonal rib is terminated a short distance from the rib r^3 . The slab B^2 is formed on one of its faces with marginal flanges $t-t-t-t$, each of which is provided at 80 the center of its length with a notch t^1 in its inner side. The aforesaid face of the slab B^2 is also formed with four diagonal ribs t^2 terminated at their outer ends at short distances from the aforesaid marginal flanges. The inner ends of said diagonal ribs are terminated with laterally enlarged heads t^3 equidistant from the center of the slab. In uniting the two slabs A^2 and B^2 they are placed one upon the other with the ribs and flanges between them, and when thus placed the heads t^3-t^3 on the inner end of the diagonal ribs t^2-t^2 of the slab B^2 abut against the central ribs r^3-r^3 of the slab A^2 while the heads s^1-s^1 of the diagonal ribs t^2-t^2 engage the flanges t at the corners of the slab B^2 , and the heads r^2-r^2 of the horizontal and vertical ribs $r-r^1$ engage the notches t^1-t^1 of the flanges $t-t$. The two slabs are thus interlocked with each other. They are to be tied together by means of either screws, or wires, or any other suitable fastening devices as hereinbefore mentioned. The center of each of the two slabs A^2 and B^2 may be provided with an orifice t^4 for the reception of a bolt for uniting the said slabs. The protruding ends of the bolt may be provided with an ornamental head and similar nut.

In Fig. 9 of the drawings I have shown an illustration of the interior of a wall constructed of a series of tiles embodying my invention in a modified form.

It will be observed that the internal ribs are interlocked with each other and with the marginal flanges of the tiles so as to effectively brace the tiles and form a strong and light hollow wall which is readily erected and

also permits of being readily taken down when desired to remove it or shift it from place to place.

What I claim as my invention is:

5 1. A tile composed of separately formed slabs disposed face to face and each of said slabs formed on its inner face with diagonal ribs extending partway across the slab and meeting the diagonal ribs of the companion slab as set forth.

10 2. A tile composed of separately formed slabs disposed face to face, one of said slabs formed on its inner face with marginal flanges, and each of the slabs formed on said face with diagonal ribs extending partway across the slab and meeting the diagonal ribs of the companion slab as set forth.

15 3. A tile composed of separately formed slabs disposed face to face, one of said slabs formed on its inner face with marginal flanges, the other of said slabs formed on its inner face with vertical and horizontal ribs across its center and each of said slabs formed on its inner face with diagonal ribs meeting the diagonal ribs of the companion slab.

20 4. A tile composed of separately formed slabs disposed face to face, one of said slabs formed on its inner face with marginal

flanges, and the other of said slabs formed with diagonal ribs disposed to interlock at 30 their outer ends with the aforesaid flanges as set forth.

35 5. A tile composed of separately formed slabs disposed face to face, one of said slabs formed on its inner face with marginal flanges, and the other of said slabs formed with vertical and horizontal ribs extending across said slab and with diagonal ribs, all of said ribs disposed to interlock at their outer ends with the aforesaid flanges as set forth. 40

6. A tile composed of separately formed slabs disposed face to face and each formed with diagonal ribs disposed parallel with and in juxtaposition to the diagonal ribs of the companion slab as set forth. 45

7. A tile composed of separately formed slabs disposed face to face, and each formed with diagonal ribs disposed parallel with and in juxtaposition to the diagonal ribs of the companion slab, and marginal flanges interlocked with said ribs as set forth. 50

JAMES A. WHEELER. [L. S.]
